Inventor
I. E. SEXTON
by myself Brown County May
1923

UNITED STATES PATENT OFFICE.

ISAAC E. SEXTON, OF WINCHESTER, MASSACHUSETTS.

OUTLET FOR CANS.

Application filed February 17, 1923. Serial No. 619,658.

To all whom it may concern:

Be it known that I, ISAAC E. SEXTON, a citizen of the United States, residing at Winchester, in the county of Middlesex and State of Massachusetts, have invented new and useful Improvements in Outlets for Cans, of which the following is a specification.

This invention relates chiefly to a sheet metal can, having a pouring nozzle projecting from the top end or head of the can, and a spout adapted to conduct liquid outward from the nozzle during the operation of pouring, the spout being adapted to swing to a projected position overhanging one side of the can, and to a retracted position over the can head.

One object of the invention is to provide a nozzle adapted to be secured to the can head, and a spout directly connected only with the nozzle, so that the movements of the spout are guided wholly by the nozzle, and not by the can head.

Another object is to so connect the spout with the nozzle that the spout is separable from the nozzle.

I attain the above-mentioned and other related objects by the improved construction hereinafter described and claimed.

Of the accompanying drawings forming a part of this specification,—

Figure 1 is a top plan view of an outlet comprising a pouring nozzle and a spout connected therewith, in accordance with the invention.

Figure 2 is a section on line 2—2 of Figure 1.

Figure 3 is a top plan view of the spout, shown by Figures 1 and 2.

Figure 4 is a section on line 4—4 of Figure 3.

Figure 5 is a section on line 5—5 of Figure 3.

Figure 6 is a perspective view of the spout.

Figure 7 is a top plan view, on a reduced scale, showing a portion of a can head and an outlet therefor, embodying the invention.

Figure 8 is a view similar to Figure 2, showing a modification.

The same reference characters indicate the same parts in all of the figures.

The nozzle element of my improved outlet is a tube, preferably of sheet metal, adapted for attachment to the head of a receptacle, such as a sheet metal can. The tube is preferably partially introverted, or turned back, to form a minor portion 13, which is

an annular flange surrounding a part of a major portion 12, and connected with the latter by an annular neck 14. The major portion may be attached to the head 16, of a sheet metal can, or other receptacle, in any suitable manner, as by being united by a seaming operation, or by solder with the head around an orifice in the latter.

The spout element is also preferably of sheet metal, and includes an inner portion 17, and an outer channeled portion 18. The inner portion has a circular orifice 19, formed to receive a portion of the nozzle, and, in this instance, the portion formed by the flange 13. The spout and the nozzle are provided with complementary interengaging connecting members, adapted to prevent rectilinear sidewise movement of the spout, and also to permit edgewise swinging movements of the spout. The rectilinear sidewise movements, which are prevented, are movements of the spout in a rectilinear direction, either toward or from the head 16. The edgewise swinging movements, which are permitted, are movements in the arc of a circle from a projected position overhanging one side of the can, as shown by full lines in Figure 7, to a retracted position over the head as shown by dotted lines.

In the preferred embodiment shown by Figures 1, 2, 3, 4, 5 and 6, the connecting member on the nozzle is an external screw-thread 13^a formed on the flange 13, and the complementary connecting member on the spout is the margin of the orifice 19, said margin being formed as an internal screw-thread.

The orifice is preferably formed on an annular boss or flange 21, and as shown by Figure 6, a portion of the boss has an outward offset 22, and an inward offset 23. Another portion has an outward offset 22^a, and an inward offset 23^a. The margin of the orifice is inclined between said offsets, so that the described formation results in the equivalent of an internal screw-thread, the arrangement being such that when the spout is placed upon the nozzle with the center of the orifice 19 alined with the center of the nozzle, and rotated in a given direction, the spout is screwed inward on the nozzle, as a nut is screwed on a bolt, until arrested by an annular stop bead 24, on the lower edge of the flange 13.

The spout may be detached from the nozzle by rotating it in the opposite direc-

tion. The described screw-thread connection permits the spout to be swung upon the nozzle from a projected to a retracted position, and although the swinging movement involves a slight movement toward or from the head 16, this is not a rectilinear movement, and does not permit the separation of the spout from the nozzle, until the spout has been given several complete rotations, and more than are likely to be caused unintentionally. Provision is therefore made for conveniently connecting the spout with the nozzle, and permitting free swinging movements of the spout, and the detachment of the spout from the nozzle, if desired.

The preferred practice is to screw the spout to its inward position on the nozzle before the latter is secured to the can head, the nozzle and spout being handled as a unit, and the nozzle, when secured, supporting the spout spaced from the receptacle head, so that rotation of the spout is not impeded by frictional contact with the head.

The separable connection provided by the screw threads enables the can to be shipped with the spout detached, and temporarily secured in a convenient position, so that it will not be liable to be distorted during shipment. I do not limit myself, however, to a separable connection, and may inseparably connect the spout with the nozzle, as shown by Figure 8. In this embodiment the interengaging members on the nozzle and spout are provided by rolling the lower end of the nozzle flange outward, to form an open annular bead 24, and by rolling the margin of the orifice 19 inward, to form an open annular bead 25, interengaged with the bead 24, to prevent sidewise movements and permit swinging movements of the spout.

It will be seen that in each embodiment of the invention, the nozzle and spout constitute an outlet which may be conveniently applied as a unit to a can, the spout being

confined and guided wholly by the nozzle. 45 The nozzle flange 13 is a desirable feature, because it enables the connecting member carried by the nozzle to be conveniently formed and located entirely outside the bore-containing portion of the nozzle. The flange 50 adds materially to the strength and stiffness of the nozzle, and is adapted to hold a flanged covering cap 26, shown by dotted lines in Figures 2 and 8, the cap flange shown by Figure 2 being screw-threaded to engage 55 the nozzle thread. The cap shown by Figure 8 is retained in place by friction.

I claim:

1. A receptacle outlet comprising a nozzle adapted for attachment to the receptacle, 60 and a spout having a circular orifice formed to receive said nozzle, said spout and nozzle being provided with complementary interengaging members, adapted to prevent rectilinear sidewise movement of the spout, and 65 permit edgewise swinging movements thereof on the nozzle, the nozzle being composed of a tube, a minor portion of which is turned back over itself to form an annular flange surrounding a major portion of said nozzle, 70 one of said interengaging members being formed on said flange, and the other on the margin of the spout orifice.

2. A receptacle outlet comprising a nozzle adapted for attachment to the receptacle, 75 and a spout having a circular orifice formed to receive said nozzle, the nozzle being composed of a tube, a minor portion of which is turned back over itself to form an annular flange surrounding a major portion of said 80 nozzle, the said flange being provided with an external screw-thread, and the margin of the spout orifice being formed to constitute an internal screw-thread separably engaging said external thread.

In testimony whereof I have affixed my signature.

ISAAC E. SEXTON.
